(57) **CLAIM**

The ornamental design for an auxiliary spectacle for protective eyewear, as shown and described.

DESCRIPTION

FIG. 1 is a top, left side, front perspective view of the auxiliary spectacle for protective eyewear of the present invention;

FIG. 2 is a front view of the auxiliary spectacle for protective eyewear of FIG. 1;

FIG. 3 is a rear view of the auxiliary spectacle for protective eyewear of FIG. 2;

FIG. 4 is a top view of the auxiliary spectacle for protective eyewear of FIG. 2;

FIG. 5 is a bottom view of the auxiliary spectacle for protective eyewear of FIG. 2;

FIG. 6 is a left side view of the auxiliary spectacle for protective eyewear of FIG. 2, the right side view being mirror image identical;

FIG. 7 is a top, right side, front perspective view of the auxiliary spectacle for protective eyewear of FIG. 2; and, FIG. 8 is a front view illustrating the auxiliary spectacle for protective eyewear mounted within a protective eyewear, the protective eyewear not part of the claimed invention.

The broken lines shown in FIG. 8 are for illustrative purposes only and form no part of the claimed design.
